UNITED STATES PATENT OFFICE.

MATTHEW R. HULL, OF CONNERSVILLE, INDIANA, ASSIGNOR TO REX MANUFACTURING COMPANY, OF CONNERSVILLE, INDIANA, A CORPORATION OF INDIANA.

CONNECTER FOR TWO-PART AUTOMOBILE DOORS.

Application filed February 3, 1925. Serial No. 6,634.

To all whom it may concern:

Be it known that I, MATTHEW R. HULL, a citizen of the United States, residing at Connersville, in the county of Fayette and State of Indiana, have invented certain new and useful Improvements in Connecters for Two-Part Automobile Doors, of which the following is a specification.

My said invention relates to a connector for two-part automobile doors and it is the main object thereof to provide a construction in which the upper edge of the demountable door section shall be biased or inclined toward the vehicle body to insure a tight fit of said section. At the same time it is desirable to bias the free or closing side of the door opposite the hinge side toward the vehicle body for the same reason. In order to do this the frame of the demountable section is flexed or strained so as to throw the upper free corner of the door inward toward the body of the vehicle to a slight extent.

Referring to the accompanying drawings which are made a part hereof and on which similar reference characters indicate similar parts,

Figure 1 is an elevation of the demountable door section viewed from the inner side, 30 Figure 2, an end elevation viewed from the left in Figure 1 or from the free side of the door,

Figure 3, a detail of a bearing pin shown at the lower left-hand corner of Figure 1, 35 Figure 4, a section on line 4-4 of Figure 1,

Figure 5, a section on line 5-5 of Figure 1,

Figure 6, a fragment on an enlarged scale 40 of parts shown in Figure 1,

Figure 7, a similar fragment of parts shown at the lower left-hand corner of Figure 1,

Figure 8, an elevation of a modified form 45 of demountable door section taken from the inner side,

Figure 9, an end elevation viewed from the left in Figure 8,

Figure 10, a section on line 10-10 of Figure 8,

Figure 11, a section on line 11-11 of Figure 8; and

Figures 12 and 13, details of parts shown in Figure 8.

55 In the drawings reference character 10

indicates the sheet metal covering at the outside of the door to which are attached wooden stiles 11, 12, 13, and 14. The stiles 12 and 13 are here shown as being reinforced by means of strips of sheet metal 15 and 16 which may be sheet steel bent substantially into L-shape to cover the inner side of the stiles and to extend partly over the outer edges and which may be fastened to the stiles in any convenient manner as by rivets extending through said strips and through the outer sheet metal covering. A plate 17 is secured to the door at the lower right-hand corner, i. e. the bottom of the demountable door section adjacent the hinge side, said plate having a downward projection with a slot at 18 to receive a screw 19. On the inner side the plate is corrugated at 20 and as will be seen from Figure 4 it is bent to provide a considerable space between the plate and an outer plate 21 having an aperture at its lower end to receive a screw 22. An internally threaded sleeve 23 engages the threaded portions of both the screws 19 and 22, said sleeve having an enlarged head 24 to bear against the outer face of the permanent door section. Said section is usually thicker than the stile 14 and for this reason the plate 17 is bent inward in the manner illustrated.

When the demountable door is placed in position on the permanent door section the sleeve 23 is first passed into a hole bored through such section and this sleeve preferably has longitudinal corrugations or other irregularities to prevent the sleeve from turning in the hole in the permanent door section.

A secondary plate 24 is provided with corrugations matching those of the plate 17 and with holes 25 to receive screws 26 for attaching it to the permanent door section. The screw 19 is capable of adjustment up and down in the slot 18 and the plate 17 can be moved up and down relatively to the secondary plate 24 which may be fixed permanently to the lower permanent door section.

This provides means for adjustment of the vertical plane of the demountable door section at the hinge side and helps to make it fit closely on the permanent section and also against the vehicle body.

In order to bias the upper edge and the free side of the door slightly toward the body to insure tight closing and prevent rattling of the door I provide at the bottom 110

of the demountable door section a rod 26 which has been so twisted as to remain normally in a twisted position, as illustrated in the two fragmentary Figures 6 and 7, which 5 show opposite ends of the rod in their normal relation. At the free side of the door I provide a strip 27 of metal, preferably steel, which may be stamped out or made in any other conventional or desirable way and 10 is fixed directly to the stile 12 or at least fixed in relation thereto. The strip is bent at its lower end, as illustrated in Figure 7 so as to provide alined apertures 28 and 29 to receive the end of the rod 26. This rod 15 is square, or at least non-circular in section at each end and the apertures are shaped correspondingly so as to hold the rod firmly against turning, the body of the rod being usually, but not necessarily, similar in cross-section to the ends:

At the other end of the rod I have provided a socket member 30 with a socket shaped to receive the end of the rod and a flat holding portion 31 having an opening 25 32 which may be threaded, if desired, to receive screw 33. The normal conformation of the rod is such that the flat portion 31 of the socket member will stand in the position illustrated in Figures 5 and 6. The end of 30 the screw passes through a plate 34 into the stile 14, the plate being held in place by bolts 35 passing through said stile. When now the screw 33 is forced down to the position shown in Figure 1, the normally twisted rod will be reversely twisted preferably until the opposite flat sides lie in parallel flat planes and will therefore strain the frame of the demountable door so as to throw the upper free corner inward in the 35 manner illustrated in Figure 2.

The position of the demountable upper door, as above described is a permanent one and this section may now be mounted on the permanent door section or be removed therefrom without changing its configuration.

An additional feature of the invention resides in an anchor plate 36 having a slot 37 through which passes a screw 38 for securing the anchor plate to the stile 14. This 50 provides for vertical adjustment of the plate on the stile after which it is fastened in place by screws 39. At its lower edge the plate has a pair of bearings 40 to receive a screw 41 which is freely rotatable in said bearings. 55 A bearing pin 42 has an internally threaded opening at its upper end to receive the threaded portion of the screw, whereby rotation of the screw serves to move the bearing pin lengthwise of the demountable door section and the screw 41. The vertical adjustment of the plate 36 and the horizontal adjustment of the bearing pin render it an 60 easy matter to vary the position of the bearing pin in accordance with the requirements of individual doors so that the demountable

section can easily be locked on permanent door sections differing slightly in form and in the position of their holes or sockets to receive the bearing pin.

In the modified form shown in Figures 8 to 13, 43 indicates the sheet metal covering at the outside of the door to which are attached wooden stiles 44, 45, 46 and 47. The stiles 45 and 47 are here shown as reenforced by strips of sheet metal 48 and 49 L-shaped 75 in section so as to extend flush with the inner line of the front metal covering 43 and down to some extent over the outer side of the respective stiles 45 and 47, which are or may be securely fastened to each other at 80 the corners of the panel in any convenient or desirable manner. A plate 50 of known character extends over the joint between the stiles 46 and 47 and has an eye at 51 through which and through an eye in a similar outer plate a bolt is passed for attaching the demountable door section to the lower permanent section which is or may be the ordinary permanent door of the automobile or other vehicle. 90

A rectangular torsion bar 52, which may be of any desirable non-circular shape in cross-section, is attached to the under side of the stile 46 said bar being held in place at one end by a socket member 53 flattened 95 at one end as indicated at 54 in Figure 13. The flattened portion is perforated to receive a screw 55 by which the socket member is attached to a casting or stamping 56 secured to the stile 46 by means of bolts 57. 100 The member 56 is here shown as having an inclined face at its left-hand end corresponding to the incline on the socket member 53 but this is not essential. The torsion rod at its other end extends through a pair of alined openings in an anchor bracket having an elongated upright arm 58 fixed to the stile 45 in any suitable manner. The bracket has a horizontal portion 59 with an angular connecting portion 60 between the parts 58 110 and 59 and an angular extension 61 at the right-hand end of the part 59, the two angular parts having openings corresponding in shape to the cross section of the rod whereby the rod is securely held by said anchor bracket at one end. 115

It will be noted that the left-hand end of the torsion rod has its sides respectively horizontal and vertical whereas the right-hand end is twisted as illustrated in Figures 10 and 11 in a manner to throw the diagonally opposite corner at the connection of stiles 44 and 45 inward toward the car thereby biasing the upper end of the demountable door and the free or closing side adjacent the stile 45 toward the body of the vehicle as is also indicated in Figure 2. In the disclosure in the drawing the rod is twisted by means of a flat part 54 on the socket member 53 resting against an inclined 125 130

face of the block 56. The torsion rod 52, which is rectangular in section, is held at its end in a socket of similar form on member 53 and the upper face of the torsion rod lies against an inclined flat face on the stile 46 which face is increasingly inclined toward the right-hand end of the stile. It will be evident that this twisted condition of the rod may be attained in other ways as, for example, the rod might have an inclined surface adjacent to the stile or the rod may be flattened and twisted at its end somewhat in the shape of the part 54 of the socket member 53. Any such methods of obtaining the desired result are considered within the purview of the invention.

An anchor plate is shown at 66, this anchor plate being preferably adjustable up and down on the stile 46 by means of a slot 20 at 62 and a screw in said slot. The anchor plate provides bearings for a screw 63 having threads engaging the threads in an opening at the upper end of the bearing pin 64 whereby the bearing pin may be moved 25 horizontally. By means of the vertical adjustment of the plate 61 and the horizontal adjustment of the bearing pin the pin may be brought into position to engage a vertical hole in the permanent door section.

Various changes in my device other than those above indicated will be obvious to those skilled in the art and therefore I do not limit myself to what is shown in the drawings and described in the specification, 35 but only as indicated in the appended claims.

Having thus fully described my said invention, what I claim as new and desire to secure by Letters Patent, is:

1. A connector for two-part vehicle doors having a lower permanent section and an upper demountable section comprising a torsion rod at the underside of the upper door section, and means for connecting the 40 ends of the rod in twisted relation respectively to said upper door section adjacent the opposite sides thereof whereby the upper end of the demountable door section will be biased toward the vehicle body, substantially as set forth.

2. A connector for two-part vehicle doors having a lower permanent section and an upper demountable section comprising a torsion rod at the underside of the upper door section, and means for connecting the 45 ends of the rod in twisted relation respectively to said upper door section adjacent the opposite sides thereof whereby the free side of the upper door section will be biased toward the vehicle body, substantially as set forth.

3. A connector for two-part vehicle doors having a lower permanent section and an upper demountable section comprising a resilient rod non-circular in cross section, and

means adjacent to opposite sides of the demountable upper section along the lower end of the same for connecting the ends of the rod to said upper section in relatively twisted relation to each other, substantially as set forth.

4. A connector for two-part vehicle doors having a lower permanent section and an upper demountable section comprising a resilient rod non-circular in cross section, and devices at spaced points along the lower end of the upper door section for connecting the ends of the rod to said upper section in relatively twisted relation to each other, one of said devices including an arm extending along the free side of the door and fixed thereto said arm having non-rotatable engagement with said rod, substantially as set forth.

5. A connector for two-part vehicle doors having a lower permanent section and an upper demountable section comprising a resilient rod non-circular in cross section, and means at spaced points along the lower end of the upper door section for connecting the ends of the rod to said upper section in relatively twisted relation to each other, said means being slidably connected to said rod, substantially as set forth.

6. A connector for two-part vehicle doors having a lower permanent section and an upper demountable section comprising an anchor plate connected to the demountable section at its lower end, said anchor plate being adjustable in one direction, and a bearing pin on said anchor plate, said bearing pin being adjustable at right angles to the adjustment of the anchor plate, substantially as set forth.

7. A connector for two-part vehicle doors having a lower permanent section and an upper demountable section comprising an anchor plate having a pair of spaced sockets, a screw journaled in said sockets, and a laterally adjustable bearing pin having threads engaging those of the screw, substantially as set forth.

8. A connector for two-part vehicle doors having a lower permanent section and an upper demountable section comprising a torsion rod at the underside of the upper door section, said torsion rod having a permanent twist, and means for connecting the ends of the rod in reversely twisted relation respectively to said upper door section adjacent the opposite sides thereof whereby the upper end of the demountable door section will be biased toward the vehicle body, substantially as set forth.

9. A connector for two-part vehicle doors having a lower permanent section and an upper demountable section comprising a normally-twisted torsion rod at the underside of the upper door section, and means for connecting the ends of the rod in reversely

twisted relation respectively to said upper door section adjacent the opposite sides thereof whereby the free side of the upper door section will be biased toward the vehicle body, substantially as set forth.

10. A connector for two-part vehicle doors having a lower permanent section and an upper demountable section comprising a normally twisted rod non-circular in cross section, and means adjacent to opposite sides of the demountable upper section along the lower end of the same for connecting the ends of the rod to said upper section said means being constructed and arranged to twist the rod back toward its original form, substantially as set forth.

11. A connector for two-part vehicle doors having a lower permanent section and an upper demountable section comprising a normally-twisted resilient rod non-circular in cross section, and devices at spaced points

25 along the lower end of the upper door section for connecting the ends of the rod to said upper section including an arm extending along the free side of the door and fixed thereto said arm being non-rotatably engaged by said rod, substantially as set forth.

12. A connector for two-part vehicle doors having a lower permanent section and an upper demountable section comprising a 30 normally-twisted resilient rod non-circular in cross section, and means at spaced points along the lower end of the upper door section for connecting the ends of the rod to said upper section in strained relation said means being slidably connected to said rod, substantially as set forth.

35 In witness whereof, I have hereunto set my hand and seal at Connersville, Indiana, this 31st day of December, A. D. nineteen 40 hundred and twenty-four.

MATTHEW R. HULL. [L.S.]
